(57) **CLAIM**

The ornamental design for a braid ponytail extension, as shown and described.

DESCRIPTION

FIG. 1 is a perspective view of a braid ponytail extension wig showing my new design;

FIG. 2 is a front view thereof, a rear view being a mirror image of the front view;

FIG. 3 is a left side view thereof;

FIG. 4 is a right side view thereof;

FIG. 5 is a front view thereof in a braided configuration; and, FIG. 6 is a perspective view thereof, shown in a braided configuration and an environment of use.

The broken line showing of the head in FIG. 6 is for the purpose of illustrating the environmental structure and forms no part of the claimed design.
